DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

FURNACE-WALL STRUCTURE.

1,275,037.

Specification of Letters Patent.

Patented Aug. 6, 1918.

Application filed October 2, 1915. Serial No. 53,668.

To all whom it may concern:

Be it known that I, DAVID S. JACOBUS, a citizen of the United States, residing at Jersey City, in the county of Hudson and State 5 of New Jersey, have invented certain new and useful Improvements in Furnace-Wall Structures, of which the following is a specification.

My invention relates to brickwork furnace walls and is designed to prevent bulging or moving inward under heat. The invention will be understood by reference to the accompanying drawings in which Fig- 10 ure 1 is a vertical section through a portion 15 of a boiler furnace, showing several ways of carrying out my invention; Fig. 2 an enlarged vertical section of a portion of the wall showing one embodiment of the invention; and Fig. 3 a perspective view of the 20 means shown in Fig. 2. Similar reference numerals indicate similar parts in the several figures.

The primary object of my invention is to provide a means for holding a furnace wall 25 so as to prevent it bulging or springing inward. Generally stated the invention consists in laying in tie pieces, in the form of metallic sheets or strips, at suitable intervals, such sheets being so constructed as to 30 give a good hold on the surfaces of the bricks composing the wall, and in securing said tie pieces at their outer ends to cross members or buckstays.

In the drawings the numerals 1 and 2 35 designate the side walls of a boiler furnace, 3 a drum of the boiler, and 4 water tubes connected to the drums. The inner lining of the walls is made up of refractory brick-work 5 laid in regular courses, and the outer 40 lining is made up of brickwork 6 laid in regular courses, and with relation to the inner lining, as indicated in Fig. 3. The particular manner of laying the courses is, however, not material to my invention. The 45 drawings indicate several methods of holding the outer ends of the tie pieces. According to one method the tie pieces 7 have their outer ends 8 bent over and passed through openings 9 formed in the horizontally 50 projecting leg of an angle-iron 10. The latter is secured to the inner face of a horizontal buckstay 11 placed outside of the wall.

According to another method, shown at 55 the left-hand side of Fig. 1, one end of the

tie pieces 7 is passed through openings in the vertically projecting leg of an angle-iron 12. The latter, in this case, is secured to the web of a horizontal buckstay 13 embedded in the wall. 60

According to the third method illustrated, one end of the tie pieces is passed through openings in the top or the bottom flange of an I-beam 14 recessed into the wall. This beam may be embedded in the wall as indicated at the left-hand side of Fig. 1, or seated in a recess in the wall as indicated at the right-hand side of Fig. 1. 65

If desired, the wall may be allowed to slip at the back of the horizontal buckstay or 70 supporting member when it changes its dimensions through expansion. In such cases the wall is formed with a pocket 16 at the outer end of each of the tie pieces, as indicated in Fig. 2. With such pockets 75 formed in the wall there can be considerable displacement of the wall either up or down with respect to the horizontal buckstay or in a direction parallel with the buckstay without affecting the holding power of the 80 tie pieces.

As shown in the drawings the inner ends of the tie pieces come a short distance within the inner face of the wall, but need not be kept far enough from the inner face to 85 prevent overheating of the pieces. Overheating of the inner ends of the tie pieces, which are ordinarily made of iron or steel, does not decrease their efficiency in holding the walls, as this converts the inner ends of 90 the pieces to a black oxide of iron which becomes cemented to the bricks. Even though the pieces may be burned to an extent which will make them shorter, the effect of this burning is to cause that portion of the end 95 which is partly burned to hold firmly through the tie pieces adhering to the brick-work.

Angle-irons have been laid in walls and held by bolts to outer stiffening members, 100 but the angle-irons burned out and their efficiency as retaining members was destroyed. With the substantially flat expanded metal pieces the inner ends may burn off but the burnt part of the metal 105 adheres to the brickwork and what is left of the expanded metal piece serves to hold the wall in position.

The tie-pieces are preferably made of a grid or mesh construction of flexible ma- 110

terial which can be readily laid between the courses of brickwork. If the bricks are forced, rubbed or pounded in place, the tie pieces will form a number of slight indentations in the bricks so as to produce a good and firm hold along the faces of the bricks, partly through friction and partly through the metal being indented into the surface of the bricks at a number of points.

10 I have used what is known in the trade as expanded metal. Such material gives a good frictional hold on the brickwork, and may be readily attached to the outer members by passing through slots and bending 15 the ends over.

What I claim and desire to secure by Letters Patent of the United States is:—

20 A furnace wall comprising a plurality of horizontal courses of brickwork, tie pieces inserted between the contiguous courses, said tie pieces consisting of metallic grids

or mesh construction of flexible material having a series of separated points or projections arranged to space apart the bricks between which it lies and to engage and frictionally hold the bricks, and wall-retaining members supported independently of the wall and to which the projecting flexible portions of said tie pieces are attached, whereby the wall is permitted to move independently of said retaining members and is prevented from bulging by reason of the holding power of said tie pieces and the stiffness of the retaining member.

In testimony whereof I have hereunto signed my name in the presence of two subscribing witnesses.

DAVID S. JACOBUS.
